Moses C. Bignall, of Seneca Falls, N.Y.
I assor to
Downs & Co of the same place
Letters Patent No 1703, dated Jan 6, 1863.

The schedule referred to in these Letters Patent and making part of the same -

To all whom it may concern:

Be it known that I, M. C. Bignall, of Seneca Falls, in the County of Seneca, and State of New York, have invented or produced a new and original Design for Pumps; and I do hereby declare that the following is a full and exact description thereof, reference being had to the accompanying drawings making part of this specification.

Fig 1. is a perspective view of the pump; and
Fig 2. a plan of the top thereof.

Like letters designate corresponding parts in
both Figs.

My Design has relation to that class of pumps known as the

Dec. 1703

"pitcher sport," which is particularly applicable for exterior use.

As represented in the drawings, the pump rests on an open or skeleton base A, of square outline from corner to corner, but with the sides a, a. of a graceful concave from the outside, inward, such as is pleasing to the eye, as represented in Fig. 1. From each corner, supports b, b. rise, gradually inclining inward, and at a suitable height a bed is formed on which rests the body of the pump, having at the lower end of the cylinder B, and directly beneath its flange c. a rounded or swelling rim C, provided at its bottom with a set of scallops or pen-dants d, d, d. as shown.

The cylinder is made of smaller diameter than the base, to preserve symmetry of form; and at its upper end the open mouth D. of the pump is gradually enlarged forming at its top, in outline, a circle having graceful scallops e, e. (Fig. 2) swelling outward suitably to give the most pleasing effect to the eye. These scallops relieve the monotony of an unbroken circle, while at the same time they avoid the harshness of the sharp angles of the octagon and other forms. To give still further effect to the scallops, I bronze or paint them suitably for the purpose. The pitcher sport E, occupies the space of one scallop, and does not interfere with the symmetry of the others.

The handle G, of the pump is made in the usual form, with the exception that it has at its outer extremity an enlargement g, surrounding an opening of suitable size, of a graceful curve at its outer end, but of a diamond shape at its inner end, as represented in Fig. 1. While this enlargement presents a pleasing effect to the eye, it also serves as a convenient rest for the hand against it.

The arrangement of the curved sides a, a. of the base, and the scallops e, e. of the mouth of the pump, are such as to present the easiest contour and most symmetrical proportion, and from similarity of outline, relieve the eye of the rigidity and monotony of plane surfaces and positive angles.

What I claim is, the Design above described and represented, consisting essentially of the concave sides a, a. of the base

and the scatlopes ~~for~~ of the mouth of the pump, arranged as specified.
In witness whereof, I have hereunto signed my name in
the presence of two subscribing witnesses.
